UNITED STATES PATENT OFFICE.

WILLIAM MAVER, JR., OF JERSEY CITY, NEW JERSEY.

TELEGRAPHY.

SPECIFICATION forming part of Letters Patent No. 326,880, dated September 22, 1885.

Application filed May 14, 1885. (No model.)

To all whom it may concern:

Be it known that I, WILLIAM MAVER, Jr., a citizen of the United States, residing in Jersey City, in the county of Hudson and State 5 of New Jersey, have invented certain new and useful Improvements in Telegraphy, of which the following is a specification.

The invention relates to the organization of the transmitting apparatus and circuits employed in multiple and other telegraph systems.

The object of the invention is to provide means for obtaining from two sources of electricity or from a single generator grounded at 15 its central point currents of different strengths and different polarities in such manner that any required number of otherwise independent systems may be operated thereby.

The invention consists, generally, in organizing the apparatus at a telegraph-station in substantially the following manner: Two generators or batteries or a single generator having its central point connected with the earth is employed as the source of electricity. For 25 convenience of description, however, reference will be had to two batteries. These have their opposite poles respectively connected with suitable pole-changing keys. These are employed for transmitting either positive or 30 negative currents to the main lines of the respective systems. Each system is provided with a transmitting key or keys adapted to substitute for the connection of the corresponding main line a connection with a point 35 intermediate between the poles of that battery—that is to say, with a point of lower potential.

The accompanying drawing is a diagram illustrating the organization of the apparatus.

Referring to the drawing, O' and O'' represent two sources of electricity, whether batteries or dynamo-electric generators. One pole—say, the negative—of the battery O' is connected with the earth at G' by the conductors 40 1 and 3. The opposite pole—that is to say, the positive—of the battery O'' , is also connected with the earth through conductors 2 and 3. The positive pole of the battery O' is connected by a conductor, 4, with a contact-point, b' , of a key, K' , which will be herein-after described, and by conductors 5 and 6

with the corresponding contact-point b' of the keys K^2 and K^3 . The negative-pole of the battery O'' is connected by conductors 19, 20, and 21, respectively, with the levers k^2 of the 55 keys K' , K^2 , and K^3 , respectively.

The keys K' , K^2 , and K^3 each consists of a lever, k , carrying at its extremity two contact-points, k' and k^2 , which are insulated from each other. The end of the lever plays between 60 two contact-arms or springs, a' and a^2 . When the key is at rest, the contact k' rests against the arm a' and presses it away from a resting-stop, d' . At the same time the arm a^2 rests against the stop b^2 . When, however, the key-lever is depressed or actuated, then the arm a^2 is raised from the stop b^2 , and the arm a' is permitted to make contact with its stop b' . The arm a' of each key is connected by conductors 7, 8, and 9, respectively, with the front 70 contact-stop, c' , of a corresponding pole-changing key, R' , while the arm a^2 is connected by conductors 10, 11, and 12, respectively, with the back stops, c^2 , of the same keys. The stop b^2 of the keys K' , K^2 , and K^3 are respectively connected by conductors 13, 14, and 15 75 with the point o^2 intermediate between the poles of the battery O'' . The contact-points are in like manner connected by conductors 16, 17, and 18 with an intermediate point, o' , 80 of the battery O' . The points k^2 are respectively connected with the negative pole of the battery O'' by conductors 19, 20, and 21. When, therefore, the two keys of any system are at rest, as shown with reference to the keys K' 85 and R' , the circuit-connections are as follows: The positive pole of the battery O' is connected with the point b' ; but at this point it is interrupted. The negative pole of the battery O'' is connected in like manner with the point k^2 , 90 but at this point the circuit is interrupted. The point o' of the battery O' is connected with the point k' , and through the arm a' with the front contact-point, c' , of the key R' ; but at this point the connection is interrupted. In 95 like manner the point o^2 of the battery O'' is connected with the point b^2 , and through the arm a^2 with the back contact-point, o^2 , of the key R' . From this point the circuit is complete through the armature lever of the key 100 R' , and this in turn is connected with the main line L' . The same systems of connections ex-

ist with reference to the other lines, L^2 and L^3 , so long as the corresponding keys are at rest. When, now, it is desired to increase the strength of a current thus caused to traverse 5 any line, it is necessary only to depress the key K' , K^2 , or K^3 . Thus if the key K^2 be closed, as shown in the drawings, the connections of the point o^2 will be interrupted at the stop b^2 ; but the conductor 20, leading from the negative pole of the battery O^2 , will be connected through the point k^2 and the arm a^2 with the back contact-stop, c^2 , of the transmitter R^2 , and thus with the main line. The full strength of the battery O^2 will thus be applied to the line 10 L^2 . The connections of the battery O^2 will meantime be incomplete, for the reason that, although the arm a^2 is placed in contact with the stop b^2 , the lever r^2 is away from the point c^2 . The keys R' , R^2 , and R^3 are employed for 15 reversing the currents sent to line, and this is effected by merely causing the armature-lever r' , r^2 , or r^3 to move toward or away from its electro-magnet. Thus, while the connections are made, as just described, with the 20 keys K^2 and R^2 , and the key R^2 be operated, the connections from the battery O^2 will be interrupted and the connections of the battery O^2 will be continued from the point c^2 through the lever r^2 with the main line L^2 . Thus a 25 positive current of full strength will be sent to line. When the pole-changing key alone is actuated, as shown with reference to the key R^3 , then a positive current of reduced strength will be sent to line, the point o^2 will 30 be connected through the conductor 18, the point k^3 , and armature a' of the key K^3 with the conductor 9, and thus through the stop c' and lever r^3 of the key R^3 with the main line L^3 . It will be seen thus that by the movements 35 of the keys K' , K^2 , K^3 , R' , R^2 , and R^3 , whether individually or two or more simultaneously, each key will serve to transmit a current having a corresponding characteristic, and all 40 these currents may be derived from the same set of batteries. This organization is especially useful at stations from which several 45 main lines proceed.

The receiving-instruments are organized and connected with the main lines in the usual manner, and do not require detailed description.

It is preferred to construct the keys R' , R^2 , and R^3 so that they will interrupt one circuit before closing another—that is to say, they 50 preferably are not continuity-preserving keys, for by interrupting the circuit there is less liability of short-circuiting the sources of electricity.

I claim as my invention—

1. The combination, substantially as herein-before set forth, with a positive and a negative source of electricity, of a series of lines, transmitting devices, substantially such as described, conductors leading therefrom, whereby any or all of said lines may be connected with either of said sources, circuit-changing keys, and circuit-connections, substantially such as described, whereby the connections of any of said lines with one or the other of said sources may be changed from a point of a given potential to a point of different potential.

2. The combination, substantially as herein-before set forth, with a positive and a negative source of electricity, of a series of telegraphic main lines, a transmitter for each of said lines, conductors leading from each transmitter to points of different potentials in each source, whereby the connections of the corresponding line may be changed from a point of highest to a point of lower potential, a second transmitter for each of said lines, and conductors leading therefrom, whereby the connections of the corresponding line may be changed from either source to the other.

3. The combination, substantially as herein-before set forth, with a positive and a negative source of electricity and a series of telegraphic main lines, of a series of transmitting-keys, one for each of said lines, each of which keys consists of a key-lever, two insulated points carried thereon, two contact-levers applied thereto, respectively, and two contact-stops applied to said contact-levers, respectively, conductors leading from one of said sources to a contact-stop of each key, conductors leading from the other source to one of the insulated points of each key, conductors leading from a point of lower potential in one source to the remaining insulated point of each key, conductors leading from a point of lower potential in the other source to one of the contact-stops of each key, a pole-changing key applied to each of said main lines, and conductors leading from the respective contact-levers of each of the first-named keys to the corresponding pole-changing key.

In testimony whereof I have hereunto subscribed my name this 12th day of May, A. D. 1885.
